(57) **CLAIM**

The ornamental design for a gun grip, as shown and described.

DESCRIPTION

FIG. 1 is a side perspective view of the gun grip showing my new design. The gun grip is mounted on a gun. The gun is rendered in broken line and forms no part of the design of the gun grip.

FIG. 2 is a side perspective view of the gun grip, the other side being a mirror image.

FIG. 3 is a bottom plan view of the gun grip.

FIG. 4 is a bottom perspective view of the gun grip.

FIG. 5 is a rear plan view of the gun grip.

FIG. 6 is a front plan view of the gun grip; and,

FIG. 7 is a side perspective view of an alternate embodiment of the gun grip, the other side being a mirror image.
